INVENTOR
Walter Coffin Strickler

UNITED STATES PATENT OFFICE.

WALTER COFFIN STRICKLER, OF PHILADELPHIA, PENNSYLVANIA.

DESIGN FOR A PICTURE-FRAME.

SPECIFICATION forming part of Design No. 23,062, dated February 13, 1894.

Application filed December 26, 1893. Serial No. 494,818. Term of patent 7 years.

To all whom it may concern:

Be it known that I, WALTER COFFIN STRICKLER, a citizen of the United States, residing at the city of Philadelphia, in the State of Pennsylvania, have invented and produced a new and original Design for a Picture-Frame, the same being fully shown in the drawing here-with accompanying, forming a part of this specification, wherein the figure shows a front elevation of my new and original design.

The leading features of my design consist of a rectangular frame having at each of its four corners a square panel carrying upon the central field thereof (first) a pair of crossed swords, (second) a pair of crossed cannons, (third) a fortification structure, and (fourth) a bugle, and having intermediate the aforesaid square panels at the several corners other

longitudinal panels bearing upon their surfaces the well-known badges of the various army corps as employed by the United States forces during the war of the rebellion. The square corner panels have a plain raised band surrounding the same and lying upon the edge thereof, while the intermediate longitudinal panels are bordered upon each edge with a beaded band.

What I claim, and desire to secure by Letters Patent of the United States, is—

The design for a picture frame as herein shown and described.

WALTER COFFIN STRICKLER.
